ABSTRACT OF THE DISCLOSURE

An upright door for an end of the horizontal chamber of a coke oven is provided in its upper part with an opening for a bar by which coal in the oven is levelled. A tubular casing is disposed in this opening and is adjustable vertically in it. The casing has a substantially horizontal passage through it, and there are means at opposite sides of the casing for bolting it to the door at different levels. The oven door is provided with substantially horizontal transverse walls extending outwardly above and below the casing and spaced therefrom. At the outer side of the door there are means closing the outer ends of the spaces between the top and bottom of the casing and transverse walls, and these spaces are filled with refractory material. The outer end of the passage through the casing normally is closed by a door, and the oven door is lined with refractory below the tubular casing.

With horizontal chamber ovens for the production of coke and gas it is desirable to vary the charging level of the coal in the ovens; for example, to suit the different shrinkage capacities of the coal, or to control the gas conversion process taking place in the gas space of the oven by varying the height of this space, or to make allowance for the position of the upper gas reversal point in the neighboring heating flues. To adjust the charging level, the track of the leveller bar, which is run in on the ram side of the oven battery through an opening in the oven door, must be adjustable vertically. This is also necessary when, at the end of part of the coking period, a layer of fine coal needs to be added and levelled by the levelling bar. To be able to vary the height of the leveller, the leveller opening in the oven door must be suitably constructed. For this purpose the leveller opening has been made large and in front of it a sealing frame is arranged that is vertically adjustable or rotatable 180°. In this case it is only necessary to give the leveller door a level that is adequate for the passage of the leveller bar. Even when using a leveller door that has sealed the larger leveller opening, the opening in the leveller door can be made smaller or moved in height by means of wedge-shaped lining pieces inserted in the leveller door frame. With such an arrangement, however, a relatively large portion of the coke oven door is exposed to the heat produced by the coking operation, so that the door becomes unusable prematurely.

It is an object of this invention to reduce the risk of damage to the oven door from the effects of heat emanating from inside the oven chamber.

The invention is illustrated in the accompanying drawings, in which

FIG. 1 is a fragmentary view of the outer side of an oven chamber closure, with the leveller door removed;

FIG. 2 is a fragmentary vertical section through an oven and its closure taken on the line II—II of FIG. 1, showing the leveller door in place;

2

FIG. 3 is a horizontal section taken on the line III—III of FIG. 2;

FIG. 4 is a fragmentary view of the inner side of the oven closure; and

FIGS. 5 and 6 are views corresponding, respectively, to FIGS. 1 and 2 but showing a modification.

Referring to FIGS 1 to 4 of the drawings, the opening at one end of the horizontal chamber 1 of a coke oven 2 is closed, during operation of the oven, by a closure 10 that includes an upright oven door that is a vertical channel having a flat web 3 and parallel vertical side flanges 4. Conventional means (not shown) hold the door in place. The door is surrounded by a sealing strip 5 that engages the frame of the oven opening. The upper part 15 of the door is provided with a rectangular opening 6 for a leveller bar. At the top and bottom of this opening there are horizontal, or nearly horizontal, walls 7 and 8 that extend outwardly between the side flanges, with which they are integral and form a frame around the opening.

Disposed in the door opening 6 is a tubular casing 10, also rectangular, that is substantially as wide as the opening but has considerably less height so that it can be moved up and down in the door. The casing has a substantially horizontal passage through it for a leveller bar. It also has integral laterally projecting bolting flanges 11 that overlap the bolting flanges 12 along the outer edges of side flanges 4 of the oven door. Integral with the top and bottom of the casing are vertical plates 13 and 14, stiffened by vertical ribs 15, that close the front ends of the spaces between the casing and the top and bottom of the frame around the door opening. The casing is held in place by bolts 16 extending through the overlapping bolting flanges and through bars 17 engaging the outer surfaces of the casing flanges. By forming the bolt holes in one pair of flanges, such as the casing flanges for example, as vertical slots 18, it becomes possible to adjust the casing vertically within limits without removing the bolts. For greater adjustment, the bolts are removed and the slots are positioned in front of different bolt holes in the door flanges before the bolts are reinserted.

The casing extends forward from the oven door. The outer end of the casing passage normally is closed by a cover 20 held in place in any suitable manner. The casing also extends from the oven door inwardly into the oven chamber. Slidably engaging the inner surface of the oven door above its opening 6 is a horizontal angle bar 21 that is secured to parallel end members 22 (FIG. 4) joined to the top of the inwardly extending portion of the casing. The space between the casing and the angle bar and top of the door opening frame is filled with heat insulating refractory material 23. A transverse rib 24 on top of the inner edge of the casing helps to hold the refractory in place. Also, the space between the bottom of the casing and the underlying frame of the door opening is likewise filled with refractory material 25. A transverse rib 26 beneath the inner edge of the casing bottom aids in holding the refractory in place. The inner face of the oven door below the casing is lined and protected by refractory blocks 27. Of course, in order to adjust the casing vertically in the oven door, the refractory material above and below the casing must first be removed. After the adjustment, the spaces above and below the casing are again filled with insulating material.

The horizontal dot and dash lines 30, 31 and 32 in FIG. 2 indicate the normal charging level 30 of the oven, the lowest possible charging level 31, and the maximum charging level 32 when using a leveller bar.

It will be seen that only a very small part of the oven door is exposed to the heat of the oven chamber. The

parts of the door located above and below the tubular casing are not exposed to unduly high temperatures because of the heat insulation. The tubular casing, which projects a considerable distance into the oven chamber, protects to a great extent the leveller door frame and the leveller cover from the intense heat.

In the modification shown in FIGS. 5 and 6, the plates above and below the tubular casing 35 are not integral with it, but are separate flat plates 36, 37 and 38, the ends of which overlap the bolting flanges 39 of the oven door 40 and are bolted to them. They close the front ends of the spaces above and below the casing and are filled with refractory material 41. The casing does not extend into the oven chamber as it does in the first embodiment. Instead, a frame 42 is connected to the inner end of the casing and slidably engages the inner surface of the oven door above and below its leveller bar opening. The lower transverse rib 43 on the bottom of the casing is at the outer end of this frame.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. A closure for an end of the horizontal chamber of a coke oven, comprising an upright oven door provided in its upper part with a leveller bar opening, a tubular casing of less height than said opening disposed in the opening and adjustable vertically therein, the casing having a substantially horizontal leveller bar passage therethrough, means at opposite sides of the casing for bolting it to the door at different levels, the door being provided with substantially horizontal transverse walls extending outwardly above and below the casing and spaced therefrom, means at the outer side of the door closing the outer ends of the spaces between the top and bottom of said casing and transverse walls, and refractory material filling said spaces.

2. A coke oven closure according to claim 1, in which said door is provided at its opposite sides with parallel vertical flanges extending outwardly, said flanges and transverse walls forming a frame for said opening.

3. A coke oven closure according to claim 1, in which said bolting means include bolting flanges along the oppo-

5

4

site sides of the door, and bolting flanges projecting laterally from opposite sides of said casing and overlying said door flanges, said flanges being provided with registering bolt-receiving openings.

4. A coke oven closure according to claim 1, in which said casing extends outwardly from said door.

5. A coke oven closure according to claim 1, in which said casing is materially longer than the thickness of the door and extends away from it in opposite directions.

6. A coke oven closure according to claim 1, including a horizontal member slidably engaging the inner surface of the door above said opening, means connecting the ends of said member to the top of said casing, and refractory material filling the space between the casing and said member.

7. A coke oven closure according to claim 1, in which said last-mentioned means are connected to said casing.

8. A coke oven closure according to claim 1, in which said last-mentioned means are plates extending across the door and bolted to it.

9. A coke oven closure according to claim 1, in which the tubular casing is rectangular with top and bottom walls, and the inner ends of said top and bottom walls are provided with transverse ribs partly overlapping said refractory material to help hold it in place.

10. A coke oven closure according to claim 1, in which said door is provided at its opposite sides with parallel vertical flanges extending outwardly, said flanges and transverse walls forming a rectangular frame for said opening, and said tubular casing is rectangular and extends away from the inner and outer ends of said frame.
